UNITED STATES PATENT OFFICE.

JOSHUA A. STRUTHERS, OF YOUNGSTOWN, OHIO, ASSIGNOR OF THIRTY-FOUR ONE-HUNDREDTHS TO W. R. BEARD, SEVENTEEN ONE-HUNDREDTHS TO J. HOWARD PARKER, AND TWENTY-FOUR AND FIVE-TENTHS ONE-HUNDREDTHS TO C. F. DUCHANOIS, OF YOUNGSTOWN, OHIO.

COMBINED DYNAMO-MAGNETO IGNITION DEVICE.

No. 841,599.

Specification of Letters Patent.

Patented Jan. 15, 1907.

Application filed August 10, 1906. Serial No. 330,082.

To all whom it may concern:

Be it known that I, JOSHUA A. STRUTHERS, a citizen of the United States of America, residing at Youngstown, in the county of Mahoning and State of Ohio, have invented certain new and useful Improvements in Combined Dynamo-Magneto Ignition Devices, of which the following is a specification, reference being had therein to the accompanying drawings.

This invention relates to a combined dynamo-magneto ignition device, the object being to provide a machine of this character adapted for use with an explosive-engine to be driven by the engine and designed to generate a current of electricity to produce the required spark for igniting the explosive agent of the engine.

A further object of the invention is to provide a continuous or constant current, the voltage being automatically regulated by an electrical governor to prevent the supply to the spark-conductors of a current of such high potential as would burn out the igniter or its conductors.

The invention comprises a generator consisting of permanent magnets, field-coils, an armature, and brushes contacting with the commutator on the armature-shaft, in combination with an electric governor for cutting the field-coils out of circuit automatically when the speed of the engine and the resultant revolution of the armature are so increased or accelerated as to generate a current or greater voltage than is required to effect the ignition.

The dynamo employed is of the shunt-wound type, the current from the armature, brushes being shunted through the field-coils in its path to the electric governor, and the electrical connections being so disposed that the strength of the current passing through the engine leads or conductors will remain substantially constant, excess current being avoided by cutting the field-coils out of circuit when the speed of the armature is accelerated to such a degree as to produce a current of greater strength than is required to produce the ignition-spark.

The construction of the improvement will be fully described hereinafter in connection

with the accompanying drawings, which form a part of this specification, and its novel features will be defined in the appended claims.

In the drawings, Figure 1 is a side elevation of a machine embodying the invention. Fig. 2 is a bottom plan view of the same, showing the electric governor or cut-out. Fig. 3 is a detail of a portion of the governor. Fig. 4 is a front end elevation of the machine, and Fig. 5 is a transverse vertical section of the same.

The reference-numeral 1 designates the armature-shaft, upon which is mounted a friction-wheel 2, adapted to run in contact with a driving-wheel of an explosive-engine.

The generator comprises a plurality of permanent magnets 3, with field-coils 4 and an armature 5, mounted upon the shaft 1.

The current from one of the usual commutator-brushes passes from a binding-post 6 through a conductor 7 to one of the field-coils 4, thence by the conductor-strip 8 to the other field-coil 4, thence by a conductor 9 to a binding-post 10 on the under side of the base of the device. The current passes through a spring-contact 11, binding-post 12, and conductor 13 to the binding-post 14, connected with the other brush of the dynamo.

The binding-posts 6 and 14 are connected by conductors 15 and 16 with the igniter of the engine and by conductors 17 and 18 with the terminals of the governor-electro-magnet coils 19.

The governor device, which is the distinguishing feature of the present invention, comprises the electromagnets 19, preferably supported under the base of the machine, and an armature 20, pivoted at one end adjacent to the binding-post 12 and secured to the contact-spring 11, the latter having an upwardly-projecting resilient arm 21, the upper end of which is adapted to engage in notches formed in an angle-plate 22, thus providing a tensioning or adjusting device for said armature.

The frame 23 of the machine is pivotally secured at one of its corners by a pivot-screw 24 to the base 25, and the other three corners of said frame are formed with inclined

elongated slots 26, through which extend securing-screws 27. A flat spring 28, preferably consisting of a plurality of plies or sections of varying length, is secured to the base 25, adjacent to the pivot-screw 24, with its free end 29 bearing against the adjacent screw 27. This construction serves to hold the friction-wheel 2 of the armature-shaft against the driving-wheel of the engine with a yielding pressure.

It will be noted that a portion of the current generated passes to the engine-igniter through the conductors 15 and 16, while the remainder of the current is shunted through the field-coils 4. The circuit comprising the conductors 17 and 18 connects the brushes with the terminals of the electromagnet-coils 19.

When the speed of the armature is sufficiently increased to generate a current greater than is required for ignition purposes, the excess current flows to the electromagnets 19, energizing the same and causing them to attract the pivoted armature 20, thus withdrawing the spring-contact 11 from the binding-post 10 and breaking the field-coil circuit at that point. This cuts out the field-coils, and consequently reduces the current to the desired degree to avoid burning out the igniter connections.

When the speed of the revolving armature is again reduced sufficiently to supply less than the amount of current required to energize the electromagnets, the pivoted armature 20 will drop by gravity and reestablish a current through the field-coils.

It will be clear that a practically constant current is maintained in the igniter-circuit, the variations of current being automatically controlled with relation to the speed of the revolving armature.

The electromagnet is so wound that it may be tapped at different points, the separate leads representing currents of varying strength to vary the amount of current required to energize said magnet.

What I claim, and desire to secure by Letters Patent, is—

1. In an electric-spark generator, the combination with permanent magnets and field-coils, of an armature revolvably supported within the generator-field, a circuit from the commutator-brushes to the igniter, a shunt circuit from the brushes through the field-coils, an electric governor comprising an electromagnet and an armature, and electric con-

nections between the terminals of said magnet-coil and the field-coils whereby when the strength of the current in said field-coils is increased, said magnet will be energized to attract its armature to break the circuit of said field-coils.

2. In an electric-spark generator, the combination with a dynamo comprising permanent magnets, field-coils and a revolving armature carrying a friction-disk, of a governor comprising an electromagnet and armature, and electrical connections, whereby a portion of the current generated passes directly to the igniter, while another portion is shunted through the field-coils, and electric connections between said magnet and the brushes, and between said magnet and the field-coils whereby the magnet will be energized when the current in the field-coils is unduly increased, to attract its armature and cut out said field-coils.

3. In an electric-spark generator, the combination with a shunt-wound dynamo, comprising permanent magnets, field-coils and a revoluble armature, of an electric governor comprising an electromagnet, and an armature carrying a contact-spring, and electric connections between the brushes of the dynamo, and the igniter, the brushes and the field-coils, the field-coils and said electromagnet, and the brushes and said electromagnet, whereby when the current is unduly increased by the speed of the revoluble armature, the field-coils will be automatically cut out to reduce the current.

4. In an electric-spark generator, the combination with a shunt-wound dynamo, comprising permanent magnets, field-coils, and a revoluble armature, of an electric governor comprising an electromagnet, and an armature carrying a contact-spring, electrical connections between the brushes of the dynamo and the igniter, the brushes and the field-coils, the field-coils and said electromagnet, and the brushes and said electromagnet whereby when the current is unduly increased by the speed of the revoluble armature, the field-coils will be automatically cut out to reduce the current, and an adjusting device for said governor.

In testimony whereof I affix my signature in the presence of two witnesses,

JOSHUA A. STRUTHERS.
